(57) **CLAIM**

The ornamental design for an inflatable pool float as shown and described.

DESCRIPTION

FIG. 1 is a perspective view of an inflatable pool float showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded perspective view of the inflatable pool float;

FIG. 10 is the perspective view as shown in FIG. 1 shown in an alternate environment of use;

FIG. 11 is another perspective view as shown in FIG. 1 shown in an additional alternate environment of use; and,

FIG. 12 is another perspective view as shown in FIG. 1 shown in another additional alternate environment of use. The dash-dash broken lines in the drawings depict portions of the inflatable pool float that form no part of the claimed design.

The additional broken lines shown in FIGS. 10-12 are for the purpose of illustrating environmental subject matter only and form no part of the claimed design.
